Application October 28, 1957, Serial No. 692,605

Claims priority, application France November 30, 1956

14 Claims. (Cl. 315—168)

The present invention relates to improvements in the design of gas or vapour-filled discharge tubes which operate by the generation and maintenance of a plasma between a pair of electrodes, anode and cathode, mounted within a sealed bulb containing the said gas or vapour atmosphere. The term "plasma" is herein defined as relating to that spatial part of a gas or vapour atmosphere wherein there exists a high and substantially equal concentration of positive and negative charges, viz. of free electrons and ions.

It more particularly relates to those of such tubes which include between the said cathode and the said anode, a control grid electrode enabling to modulate the said plasma and the anode current of which is consequently controlled from a so-called "alternating" signal (which may have the waveform of a sine wave or a saw-toothed or square wave or any other similar waveform) or from a D.C. signal, the amplitude of which varies in a continuous fashion.

The initiation and maintenance of the discharge in such tubes have been obtained until now by applying between or across the anode and the cathode thereof a potential difference at least equal to the ionising potential value of the concerned atmosphere. Consequently such tubes could not be directly introduced into electrical circuits supplied from a low voltage battery of say, 24 volts at the higher value thereof. From another point of view, the energy consumption of such tubes was relatively high from this very necessity of a high voltage difference across anode and cathode thereof. Such an energy consumption was further increased from the fact that it was most commonly needed to incorporate therein thermionic cathodes for obtaining the required current deliveries therefrom. From a further point of view, and still with respect to that need of a high potential difference between anode and cathode thereof, the so-called miniaturizing process could not easily be applied to such tubes as this implied drastic conditions for the heat dissipation therefrom. Such a set of drawbacks and limitations had led to a restriction in the use of such tubes whereas, on the other hand, they present a definite interest in that they are useful and advantageous current amplifiers. The plasma thereof, which is electrically neutral, is a quite good conductor, as is well known, and consequently presents a low resistivity, it is then adapted to support currents of high intensity suitable for such a high gain current amplification process.

According to the present invention, the initiation and maintenance of the plasma in such tubes as hereinabove specified are obtained from the incorporation to the structure thereof of a beta-particle emitter. The radiation of particles from the said emitter then produces from collisions of the said particles with the molecules of the gas atmosphere within the bulb a permanent ionization of the said atmosphere, though only a quite reduced potential difference is applied across the cathode and anode thereof, much lower than that which would have

2

been needed for producing the ionization of the said atmosphere. The potential difference applied across the cathode and anode of a discharge tube according to the invention could not either initiate or maintain by itself the plasma in the said atmosphere but it suffices, as this plasma exists, for enabling the circulation therethrough of a high intensity current which may be picked up in the anode circuit of the said tube from which a load is fed, and this current is controlled by the signal applied to a control grid inserted between the anode and cathode of the said tube. The action of such a signal is quite conventional per se, acting on the number of electrons emitted from the cathode and which reach the anode of the tube.

In a preferred embodiment of the invention, all electrodes of the tube are made coaxial and the beta particle emitter is provided as a film deposit either on the internal surface of a hollow rod the outer surface of which bears the electron emissive layer of the cathode, or on a plurality of rods evenly distributed around the cathode and in close proximity thereof. Such an arrangement avoids the necessity of any screen for the bulb against the action of the beta particles, as the anode of the tube may be made of a suitable material therefor, and further it increases the electron emission from the cathode layer as the action of the beta particles therefor adds to that of the ions of the gas atmosphere for extracting electrons from the said cathode. Consequently, a discharge tube according to the invention may be made with a non-thermionic but cold cathode.

For further disclosing the features of the invention, reference will be made to the single figure of the accompanying drawing. Of course such technological details as seals and spacers are not shown and will not be referred to, as being apparent from the conventional techniques.

The bulb of the tube, which may be considered as cylindrical is shown at 1 and contains a gas atmosphere introduced therein after the mounting of the electrodes, viz. an anode 2, a control grid 3 and a cathode the emissive layer of which 4 is formed over the outer face of a thin hollow cylinder 5, over the inner face of which has been formed a thin layer or film of a material which emits beta particles, viz. a radio-isotope.

The emissive layer of the cathode may consist of a layer of carbonates and/or nitrates and/or oxides of such elements as barium, strontium or any other elements known to produce a substantially high number of electrons when activated. This layer may be formed over a very thin cylinder of a metal such as nickel for instance, which only affects in a practically negligible way the passing therethrough of the beta particles from the film 6 on the inner face thereof. The thickness of the metal may for instance be of about 25 microns. This layer 6 may have been obtained in any suitable way and for instance from a heat evaporation process, a chemical reaction of a radio-isotope salt or a precipitation or sedimentation thereof. The radio-isotope material is chosen amongst those which emit a beta ray for taking advantage of the fact that such a kind of radiation has only a small penetration power and consequently does not necessitate stressing conditions for the handling thereof. It is of course apparent that the said radio-isotope material must have a conveniently lengthy period so that this period reaches or exceeds that of the useful life contemplated for the concerned discharge tube (such a useful life is mainly defined by that of the cathode emissive layer and/or the reduction of the atmosphere pressure with the time). It is not necessary to have recourse to such radio-isotopes the useful life of which exceeds several years through other considerations and mainly economical ones may lead to use some isotope

of this kind. It may be for instance the one known as Silicium 31, the useful life of which is of 14 years; or for tubes of shorter life, it may be that known as Thallium 204, the useful life of which is equal to 2.7 years. As concerns isotopes of lengthy useful life but of acceptable price, one may cite the Carbon 14 the life of which is equal to 5400 years.

From the point of view of the specific activity which is required from a radio-isotope as used in a tube according to the invention, it may be noted that in a design of such a tube and for a predetermined geometry of the electrode structure thereof, one may base the estimation on the evaluation of the number of ions produced within the gas atmosphere by the beta particles. Such an evaluation takes into account the following factors: energy of the isotope, expressed in electron-volts, weight of the said isotope in the structure, intrinsic characteristics of the gaseous atmosphere (diameter of the molecules of the gas and capture section thereof), and conditions imposed to the said atmosphere (number of molecules per cubic centimeter, according to the pressure and temperature thereof, volume of the bulb).

The choice of the gas defines, at some extent at least, the potential difference value to be applied across the cathode and anode of the tube for the utilization thereof, viz., the E.M.F. value of the battery 7 connected across the said electrodes. When helium or neon is used, the potential difference may be lower than 24 volts. For hydrogen, nitrogen, argon, krypton or xenon, this potential difference may remain lower than 12 volts. For a metallic vapour, such as quicksilver, cadmium or other, that potential difference may remain lower than 6 volts.

The possibility of using a cold cathode for the major part of the possible uses of such a discharge tube is mainly due to the fact that the beta particles themselves produce the extraction from the electron emitting layer of the cathode (and at a lesser degree of secondary electrons from the grid and anode material) of a substantial number of electrons; the action of the said particles adds to that of the ions which normally ensure such an extraction from the said cathode. Of course for high power discharge tubes, it will be possible to have recourse to thermionic cathodes in order to increase the volume and density of the plasma and consequently the average value of controllable power from the tube. Nothing impedes in such a case that the heater filament for the thermionic cathode receives part at least of the beta particle emitter material.

On the other hand, it must be emphasized that as much as possible the beta particle emitter material must be protected against impact of ions onto it. Such a condition apparently is satisfied in the shown structure of discharge tube. When, for technological purposes, the location of the emitter within the cathode cylinder could not be maintained, the radio-isotope could then be deposited over thin rods evenly arranged around the cathode and preferably within the "black" space around the said cathode in the plasma atmosphere, and each film of isotope would be protected by a shield or screen from the impact of ions from the plasma, such a shield consisting for instance of a nickel cylinder of some tens of microns of thickness thereof.

For arranging a gas discharge tube according to the invention as a signal amplifier, a battery voltage is also applied across the cathode and control grid thereof, for instance from a battery shown at 10 in the drawing. The control grid is negatively biased with respect to the cathode and the input control signal may then be applied across the input terminals 12 which are terminals of a series-connected impedance member 11, for instance a mere resistor. The amplified signal may be collected across a load impedance 8, serially connected into the cathode to anode circuit. The output terminals toward any utilization equipment are shown at 9. For an A.C. input signal, the impedance 8 may consist of the

primary winding of a transformer. For an input D.C. signal, the said impedance 8 may consist of a mere series resistor.

What is claimed is:

1. A gas-filled discharge tube comprising at least a cathode having an electron emissive layer, an anode and a control electrode within a single envelope and a radioactive particle emitter in cooperative association with the gas for maintaining the gas between the anode and cathode in ionized condition due solely to collision between the particles and gas molecules whereby only a small potential difference is needed across the cathode and anode of the tube for defining the value of the discharge current through the thus initiated and maintained plasma.

2. A gas filled discharge tube as in claim 1, wherein the said particle emitter is a beta-particle emitter material.

3. A gas-filled discharge tube in accordance with claim 2 in which the anode, cathode, control electrode and particle emitter are mounted within the envelope and including shielding means between the particle emitter and the ionizable gas which is impervious to the ions but pervious to the emitted beta particles.

4. A tube according to claim 3 in which the said shield comprises a cylinder supporting on the outer face thereof the electron emitting layer of the cathode of the tube.

5. A gas-filled discharge tube in accordance with claim 3 including a plurality of thin rods in close proximity to the electron-emissive layer, said rods supporting the particle emitting layer and the shielding means.

6. A tube according to claim 2, wherein the said beta ray emitting material is selected from a group comprising Silicium 31, Carbon 14 and Thallium 204.

7. A tube according to claim 1 and wherein the cathode of the tube is of the cold cathode type.

8. A tube according to claim 1 wherein the cathode of the tube is of the thermionic kind.

9. A tube according to claim 3 wherein the electrodes are cylindrical and in nested relation, the anode being the external electrode and the beta ray emitting material consists of a film over the inner face of the cylindrical metallic tube supporting the electron emitting layer of the cathode.

10. A tube according to claim 3, wherein the said shield is of thin nickel.

11. A tube according to claim 1 wherein a positive biasing battery is connected across the anode and cathode thereof and a negative bias battery is connected across the cathode and control grid thereof, a series input signal receiving impedance in the said cathode to control grid connection and a series output signal collecting impedance in the cathode to anode connection thereof.

12. A tube according to claim 1 wherein the gas is selected from a group consisting of neon, helium, nitrogen, hydrogen, argon, xenon, krypton, quicksilver and cadmium vapors.

13. A tube according to claim 3 wherein the beta ray shield is between the said beta ray emitter and the envelope of the tube.

14. A tube according to claim 8 wherein part at least of the beta ray emitting material is deposited over the heater filament of the thermionic cathode of the tube.
